US00D835376S

(12) **United States Design Patent** (10) **Patent No.:** **US D835,376 S**
(45) **Date of Patent:** **** Dec. 4, 2018**

(54) **TRASH CAN**

(71) Applicant: **simplehuman, LLC**, Torrance, CA (US)

(72) Inventors: **Frank Yang**, Rancho Palos Verdes, CA (US); **Di-Fong Chang**, Torrance, CA (US); **Myk Lum**, Irvine, CA (US); **Adam Wade**, Rancho Santa Margarita, CA (US); **Helen Miller**, Diamond Bar, CA (US)

(73) Assignee: **simplehuman, LLC**, Torrance, CA (US)

(**) Term: **15 Years**

(21) Appl. No.: **29/584,385**

(22) Filed: **Nov. 14, 2016**

(51) **LOC (11) Cl.** **09-09**

(52) **U.S. Cl.**

USPC **D34/9**

(57) **CLAIM**

The ornamental design for a trash can, as shown and described.

DESCRIPTION

FIG. 1 is a top, front, left-side perspective view of a trash can embodying our design;

FIG. 2 is a top, rear, right-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and

FIG. 8 is a bottom plan view thereof.

FIG. 9 is a top, front, left-side perspective view of a second embodiment of a trash can embodying our design;

FIG. 10 is a top, rear, right-side perspective view thereof;

FIG. 11 is a front elevation view thereof;

FIG. 12 is a rear elevation view thereof;

FIG. 13 is a right-side elevation view thereof;

FIG. 14 is a left-side elevation view thereof;

FIG. 15 is a top plan view thereof; and,

FIG. 16 is a bottom plan view thereof.

The broken lines in the figures are for the purpose of illustrating portions of the trash can that form no part of the claimed design.

1 Claim, 14 Drawing Sheets
